SPARK-RETARDING MECHANISM

Application filed May 31, 1928. Serial No. 281,944.

This invention relates to improvements in the independently operable spark control and electric starting mechanisms of internal combustion engines and aims primarily to associate and inter-relate such mechanisms in such a manner to effectually and positively prevent starting of such engines with their spark control mechanisms in advanced positions, thus minimizing the tendency of back-firing on starting and the consequent damage to the starting mechanisms ordinarily resulting therefrom.

Contemplated by the present invention is a spark retarding mechanism, whereby the engine equipped therewith can only be started when its distributor mechanism is in a fully retarded position, which is especially designed to be interposed between the hand operated spark control rod of the engine and the correlated distributor thereof, and which is adapted to be actuated by means for closing the circuit of the starting motor, to fully retard the spark prior to the closing of said circuit, all of which are important objects of the invention and are to be correlated in the broad aim of enhancing the efficiency of the mechanism for general use.

The above and additional objects which will be hereinafter more specifically treated, are attained by such means as are shown in the accompanying drawings, described in the following specification and then more clearly pointed out in the claims, which are appended hereto, and form a part of this application.

With reference to the drawings in which there are illustrated several embodiments of the invention, and throughout the several views of which like characters of reference designate similar parts.

Figure 1 is a fragmentary perspective view of an automotive vehicle equipped with the spark retarding mechanism comprehended by the present invention.

Fig. 2 is an enlarged side elevation of the spark retarding mechanism, in an inactive position, as it would appear when its correlated distributor mechanism is in a full spark advanced position.

Fig. 3 is an end elevation of the same in a full spark advanced position, certain parts

thereof being shown in section for clarity of illustration.

Fig. 4 is a similar view with the several parts shown in a full spark retarded position.

Fig. 5 is a section taken through 5—5 of Fig. 3, with the parts in a full spark advanced position in full lines and in a full spark retarded position in dot and dash lines.

Fig. 6 is a section taken through 6—6 of Fig. 2, with the parts in a full spark advanced position in full lines and in a full spark retarded position in dot and dash lines, but with the starter switch of the electric starting mechanism open.

Fig. 7 is a similar section with the parts in a full spark retarded position and with the starter switch closed.

Fig. 8 is a fragmentary horizontal section taken through 8—8 of Fig. 1 with the distributor arm in a full spark advanced position in full lines and a full spark retarded position in dot and dash lines.

Fig. 9 is a fragmentary perspective view of a slightly modified type of spark retarding mechanism.

Fig. 10 is a similar view of still another modified type of spark retarding mechanism.

Fig. 11 is a fragmentary side elevation, partly in section, of a slightly modified type of spring mechanism for returning the spark retarding mechanism to an advanced position following actuation thereof, and

Fig. 12 is a transverse section taken through 12—12 of Fig. 11.

Before taking up the detailed description of the drawings, a general exposition of the specific purposes, features, and functions of the spark retarding mechanism evolved by the present invention will be undertaken. With the present independently operable spark control and electric starting mechanisms of internal combustion engines for automotive vehicles, it frequently occurs that a vehicle operator, especially in dense traffic or under other congested conditions, in the event his vehicle stalls, will attempt to start his engine with the spark control mechanism in a full advanced position, resulting in many instances in back-firing of the engine, which is very injurious to the starting mechanism.

causing as it does breakage of starter parts, stripping of gears and other damage to the engine. Further, it frequently occurs, especially with student operators or beginners, that such operators will forget and omit to advance the spark control mechanism after starting of the engine, and in consequence will drive long distances with the spark control mechanism in a full or substantially retarded position, thereby causing undue heating of the engine and resulting in considerable and sometimes irreparable damage to the engine blocks. I am fully aware that automatic spark retarding mechanisms have heretofore been employed in the distributors of automotive vehicle engines, but such mechanisms did not provide for a full and complete spark retarding movement during starting periods, and a further objection and disadvantage of said mechanisms is that it is necessary for the engine to attain considerable speed before the automatic spark mechanism will function to advance the spark, in other words advancing of the spark is subsequent to the picking up of speed of the engine. It is, therefore, a primary object of the present invention to associate and interrelate the spark control and electric starting mechanism of an automotive vehicle engine, in such a manner, that starting of such engine cannot be effected or secured unless the spark control mechanism is in a full retarded position, thus effectually and positively preventing back-firing of the engine and breakage or damage to the starter, or other correlated engine parts. A further primary object is to obviate and prevent an inexperienced operator from driving any distance with his spark control mechanism in a retarded or partially retarded position, inasmuch as the spark control mechanism is automatically advanced immediately upon starting of the engine, thereby eliminating or materially reducing undue heating of the engine from this cause. A still further primary object is to positively secure advancement of the spark control mechanism prior to the speeding or pick up of the engine, which advancement is immediately and automatically obtained upon starting of the engine; this pertinent and novel feature is highly desirable.

Beginning the more detailed description by reference to the accompanying drawings, the numeral 15 designates an automotive vehicle having a steering post 16, within which is mounted an oscillative spark control rod 17 provided at its upper projecting end with a hand-operated spark lever 18 and at its lower projecting end with an arm or lever 19, to which is pivotally connected an adjustable rod 20 having a tubular outer terminal portion 21, within which is slidably disposed for axial movement a spring-pressed rod 22 pivotally connected at its

outer or opposite end to a spark control bell crank 23 mounted for oscillative movement upon a fixed portion 24 of the vehicle. The bell crank 23 is connected by a transversely disposed rod 25 to an arm 26 of a distributor 27 interposed in the ignition system of the vehicle, whereby said distributor may be oscillated between full spark advanced and full spark retarded positions, and for this purpose the arm 26 is provided with an arcuate slot 28, wherethrough a pin 29 extends, which pin is rigidly secured to a fixed portion 30 of the vehicle, which also functions as a bearing for the rotative shaft 31 of the distributor. It will thus be obvious and apparent that the slot 28 and pin 29 effectually and positively limit oscillative movements of the distributor 27 between full advanced and full retarded positions.

Pivottally connected to the spring-pressed rod 22 is one arm of a bell crank 32, which latter is mounted for oscillative movement upon a fixed portion 33 of the vehicle, and similarly connected to the other arm of said bell crank is a rearwardly extending longitudinally disposed adjustable rod 34 having a tubular rear terminal portion 35, within which is slidably disposed for axial movement a spring-pressed rod 36, which extends rearwardly therefrom in axial prolongation thereto and at its rear end is pivotally connected to one end of a foot actuated pedal 37 oscillatively mounted substantially midway of its length upon the sloping foot board 38 of the vehicle in proximity to the vehicle starting switch 39, said pedal preferably having a disk 40 of insulating material rigidly secured upon the underside adjacent to its outer or free end, which latter is normally maintained in spaced superimposed relation with respect to the starting switch 39, as indicated in full lines in Figs. 1, 2 and 6, so that when the pedal 37 is depressed by the foot of the operator, as shown in dot and dash lines in Fig. 6 and full lines in Fig. 7, said pedal will contact with and actuate or close such switch and thereby start the engine.

For reasons hereinafter apparent, it is to be here noted that the spring of the spring-pressed rod 22 should be relatively light, while the spring of the spring-pressed rod 36 should have at least twice the resistance to compression than has said first mentioned spring.

In starting an engine equipped with the mechanism of the present invention the operator leaves the hand operated spark lever 18 in full spark advanced position and depresses the pedal 37 with his foot, whereby a pull is exerted upon the spring-pressed rod 36 which due to its heavier spring imparts such pull to the rod 34 to oscillate the bell crank 32, whereby a pull is exerted upon the spring-pressed rod 22, which having the

lightest spring compresses same and is caused to move outwardly in its tubular terminal 21 and thereby impart oscillative movement to the spark control bell crank 23, which causes longitudinal movement of the transverse rod 25, whereby the distributor arm 26 is oscillated from its full spark advanced position shown in full lines in Fig. 8 to its full spark retarded position shown in dot and dash lines in said figure. When the arm 26 has reached its limit of movement as above described, the pedal 37 is substantially in the position indicated in dot and dash lines in Fig. 6, the starter switch 39 being still open, so that continued depression of such pedal, will compress the spring of the rod 36 and the latter will move outwardly from its tubular casing to permit the pedal 37 to assume the position indicated in Fig. 7, whereat the switch 39 is closed to start the engine, whereupon the operator removes his foot from the pedal 37 and the springs of the rods 22 and 36 automatically return the mechanism to the full spark advanced position indicated in full lines in the drawings. It is to be here noted, during starting of the engine in the manner just described, that the arm 19 and correlated rod 20 and casing 21 remain inactive, however, if at anytime it is desired to retard the spark by the hand operated lever 18, such lever is actuated in the usual manner to oscillate the arm 19, which in turn imparts movement to the bell crank 23, through the media of the rods 20 and 22, substantially in the identical manner, as though said arm and bell crank were interconnected with a solid single rod, thus it will be manifest and apparent that the present, improved spark retarding mechanism does not interfere in any way with the functioning of the hand operated control 18.

In the slightly modified type of spark retarding mechanism disclosed in Fig. 9, the bell crank 32 is omitted and the actuating pedal 37 is disposed upon the opposite side of the starter switch 39, which necessitates attaching the forward end of the adjustable rod 34 to an arm 41 rigidly secured to the distributor 27, whereby depression of the pedal 37 will directly oscillate such distributor from a full spark advanced position, prior to the closing of the switch 39.

In the slightly modified type of spark retarding mechanism shown in Fig. 10, the adjustable rod 20 and spring-pressed rod 22 are omitted and a solid rod 42 is substituted therefor, to which is connected the bell crank 32, a relatively light helical spring 43 connected at one end to the arm 19 of the spark control rod 17 and at its opposite end to a fixed portion 44 of the vehicle serves and functions thereto to return the arm 19 to a normally advanced position following starting of the engine.

In Figs. 11 and 12, I have shown a spiral

type of spring 45 enclosed in a casing 46 rigidly secured to a fixed portion 47 of the vehicle, which spring may be substituted for the helical spring 43, above described, and functions to return the arm 19 to a normal spark advanced position.

Manifestly, therefore, automotive vehicles equipped with the present mechanism may be efficiently and safely started by student drivers, without any fear of damaging the engines thereof, inasmuch as the spark controlling mechanisms being automatically retarded prior to the starting of their engines and similarly advanced subsequent to starting, will prevent back firing of the engines. Further with such automatic actuation of the spark controlling mechanisms student drivers and beginners may devote their entire attention to the care and steering of the vehicles in dense traffic, and in the event their engines stall under such conditions, the same may be started without manipulating the hand control spark levers.

From the foregoing it will be obvious and apparent, that the mechanism of the invention is extremely simple, durable and economical in construction, is convenient to use, is efficient, positive and reliable in operation, will not readily get out of order, and will not permit starting of its correlated internal combustion engine when the distributor mechanism thereof is in an advanced position.

While I have herein shown and described my invention with sufficient detail to enable those skilled in the art to understand the mode of construction and the principles involved, it is to be understood that there is no intentional limitation herein to the specific form and precise details of construction of the invention herein shown and described, except as expressly defined by the appended claims, and that various modifications of said construction may be resorted to without departing from the invention, or the benefits derivable therefrom. I also desire to have it understood that certain features of the invention herein disclosed may be employed in other combinations than those herein shown.

Having thus fully described my invention, what I claim as new and desire to secure by Letters Patent is:

1. The combination with the spark control mechanism and the starting motor switch of an internal combustion engine; of means connected to the control mechanism and operable primarily to move the same to full spark retarded position and then to abut and close said switch, comprising a pedal having one end thereof overlying said switch in normal spaced relation thereto, a spring-pressed telescopic rod connected at its rear end to the opposite end of said pedal, an operative connection between the forward end of said telescopic rod and said spark control mechanism,

- and hand actuated means for retarding said control mechanism independently of said pedal including a spring retracted rod the spring of which is light relative to the spring of said telescopic rod.

2. The combination with the spark control mechanism and the starting motor switch of an internal combustion engine; of means connected to the control mechanism and operable primarily to move the same to full spark retarded position and then to abut and close said switch, comprising a pedal having one end thereof overlying said switch in normal spaced relation thereto, a spring-pressed telescopic rod connected at its rear end to the opposite end of said pedal including a relatively heavy compression spring, an operative connection between the forward end of said telescopic rod and said spark control mechanism, and hand actuated means for retarding said spark control mechanism independently of said pedal including a telescopic spring-pressed rod having a relatively light compression spring.

3. The combination with the spark control mechanism and the starting motor switch of an internal combustion engine; of means connected to the control mechanism and operable primarily to move the same to full spark retarded position and then to abut and close said switch, comprising a pedal having one end thereof overlying said switch in normal spaced relation thereto, a longitudinally adjustable spring-pressed telescopic rod connected at its rear end to the opposite end of said pedal, hand actuated means for retarding said spark control mechanism independently of said pedal, and means operatively interconnecting the forward end of said telescopic rod with said hand actuated means and said spark control mechanism.

4. The combination with the spark control mechanism and the starting motor switch of an internal combustion engine; of means connected to the control mechanism and operable primarily to move the same to full spark retarded position and then to abut and close said switch, comprising a pedal having one end thereof overlying said switch in normal spaced relation thereto, a spring-pressed telescopic rod connected at its rear end to the opposite end of said pedal, hand actuated means for retarding said spark control mechanism independently of said pedal including a spring-pressed telescopic rod, a bell crank interconnecting said telescopic rods, and means for interconnecting said last named telescopic rod with the spark control mechanism.

5. The combination with the spark control mechanism and the starting motor switch of an internal combustion engine; of means connected to the control mechanism and operable primarily to move the same to full

spark retarded position and then to abut and close said switch, comprising a pedal having one end thereof overlying said switch in normal spaced relation thereto, a spring-pressed telescopic rod connected at its rear end to the opposite end of said pedal and having a relatively heavy compression spring, hand actuated means for retarding said spark control mechanism independently of said pedal including a spring-pressed telescopic rod having a relatively light compression spring, means for interconnecting the adjacent ends of said telescopic rods, and means for connecting the second mentioned telescopic rod to the spark control mechanism.

6. The combination with the spark control mechanism and the starting motor switch of an internal combustion engine; of means connected to the control mechanism and operable primarily to move the same to full spark retarded position and then to abut and close said switch, comprising a pedal having one end thereof overlying said switch in normal spaced relation thereto, a spring-pressed telescopic rod connected at its rear end to the opposite end of said pedal, hand actuated means for retarding said spark control mechanism independently of said pedal including a spring-pressed telescopic rod, means for interconnecting the forward end of the first mentioned telescopic rod with the inner end portion of said last mentioned telescopic rod, a bell crank pivotally connected to the inner terminal of the latter, and a rod connecting said bell crank with the spark control mechanism.

In testimony whereof I affix my signature.
JESSE C. COHEE.
